(57) **CLAIM**

I claim the ornamental design for a childproof container, as shown and described.

DESCRIPTION

FIG. 1 is a perspective view of a childproof container showing the new design;

FIG. 2 is a bottom view of the childproof container;

FIG. 3 is a right side view of the childproof container;

FIG. 4 is a top view of the childproof container;

FIG. 5 is a left side view of the childproof container;

FIG. 6 is a rear view of the childproof container;

FIG. 7 is a front view of the childproof container;

FIG. 8 is a perspective of a first part of the childproof container, shown separately to show aspects of the design that are not visible when combined;

FIG. 9 is top view of the first part of the childproof container;

FIG. 10 is a right side view of the first part of the childproof container;

FIG. 11 is a bottom view of the first part of the childproof container;

FIG. 12 is a rear view of the first part of the childproof container;

FIG. 13 is a front view of the first part of the childproof container;

FIG. 14 is a left side view of the first part of the childproof container;

FIG. 15 is a perspective view of a second part of the childproof container, shown separately to show aspects of the design that are not visible when combined;

FIG. 16 is a top view of the second part of the childproof container;

FIG. 17 is a left side view of the second part of the childproof container;

FIG. 18 is a rear view of the second part of the childproof container;

FIG. 19 is a front view of the second part of the childproof container;

(Continued)

FIG. 20 is a bottom view of the second part of the childproof container; and,
 FIG. 21 is a right side view of the second part of the childproof container.
